UNITED STATES PATENT OFFICE

1,989,244

ABDOMINAL TRUSS

Charles Nygard, Branford, Conn.

Application August 10, 1932, Serial No. 628,229

1 Claim. (Cl. 128—112)

The present invention relates in general to surgical appliances and has particular reference to an improved abdominal truss for the treatment of hernias.

The primary object of the invention is to provide a truss of the class described which is designed to treat the rupture and the area immediately around the same in a way to improve the condition of the rupture and materially aid in restoring the rupture to a natural condition.

A further object of the invention is to provide a truss which may be conveniently worn upon the person without the discomfort usually experienced in devices of this kind.

With these and other objects in view the invention will be more clearly understood upon reference of the accompanying drawing in which;

Fig. 1 is a perspective view of the truss as it will appear when applied upon the person;

Fig. 2 is a detail in front elevation of the pad and the cooperating resilient part of the waist encircling member or belt; and,

Fig. 3 is a detailed view in cross section of the pad structure.

One embodiment of the invention is presented herein for the purpose of illustration but it will of course be understood that the invention is susceptible of other different modified embodiments which come equally within the scope of the appended claims.

Referring to the embodiment shown in the drawing 1 represents a waist encircling member or belt. This belt is preferably produced from some non-elastic material suitable for the purpose having a felted inner surface 2 which will present a soft non-irritating body contact surface. This felted inner surface may be realized by applying a separate strip to the inside of the belt or it may be produced by selecting a belt having material of these qualities.

Detachable secured to the belt 1 by means of elastic straps 3, with snap fasteners 4, are a pair of hip cushions 5 and 6 respectively. These cushions are preferably made of relatively thick soft material having satin or silk inner surfaces so as to offer the utmost comfort to the wearer. The cushions may be stuffed with soft material such as cotton or the like, or else they may be made up of a laminated structure in which superimposed layers are sewed together. This is more or less immaterial so long as the cushion effect is realized and the inside of the cushions are provided with satin, silk or the like soft material. By means of the elastic straps 3 the position of the cushions may be shifted on the belt

to accommodate the same to the wearers' liking. These straps 3 also enable the cushions to be removed from the belt 1 when occasion demands. The cushion 5 is made with a depending skirt 7 to offer additional protection to the wearer at the point of connection of the crotch strap 8. In this connection a strap 9 is looped around the belt 1 with a buckle 10 carried thereby for engaging the free end of the crotch strap 8. The position of the strap 9 on the belt 1 may be shifted so as to arrange the crotch strap 8 at the convenience of the wearer. The strap 8 passes between the legs of the wearer and its opposite end carries a metal eye 12 which detachably engages a stud 13 on the pad 14, which will be hereinafter more specifically described. The strap 8 is preferably made of elastic material and is covered with silk, satin or some other soft material for the comfort of the wearer. The free end 11 of the strap 8 overlies the depending skirt 7 of the cushion 5 which further makes the device more comfortable to wear than it would be in the absence of the skirt 7.

The body encircling member or belt 1 is connected around the waist of the wearer by means of a buckle 15.

Referring now to the pad 14 attention is invited particularly to the cross section view in Figure 3. As is customary in devices of this kind the pad is made as a modified oval shaped device 30 and in my particular case the material of the pad is either sponge rubber, gutta-percha or any other material suitable for the purpose. In constructing the pad I provide a metal shell 16 which will be inset within the pad 14 and secured therein by screws, rivets or the like 17 after the manner shown in Figures 2 and 3. The shell 16 will be formed with a central channel 18 to admit a sliding member 19 which is slidably carried on the back of the cover plate 20. Anchored as at 21 at one end of the channel 18 is a spring or springs 22 anchored as at 23 to the sliding member 19. The cover plate 20 is made with a slot in its thickness to expose the sliding member 19 so as to secure the stud 13 thereto through the medium of the stud plate 24 which is fastened to the sliding member by screws, rivets or the like.

With the parts of the pad assembled in this manner and with the crotch 8 secured to the stud 13 through the medium of the metal eye 12 50 the crotch strap is held taut by means of the spring or springs 22. This arrangement, as a result of adjusting the crotch strap by means of the buckle 10, will impart a downward pull to the pad 14 under the yielding influence of the 55

spring or springs 22 thus maintaining the pad in proper position under the influence of a resilient restraining force.

The body encircling member or belt 1 is equipped with a metal plate 25 which is secured to the plate 20 of the pad by means of screws, rivets or the like and thus the pad is carried by the belt. To the left of this plate 25, viewed from the front as in Figure 2, the belt end which carries the buckle 15 is preferably made of elastic material 26. In other words a short length of elastic material is used for the belt end which carries the buckle 15. The reason for this is to accommodate a spring device 27. This spring device preferably comprises a pair of metal end plates 28 and 29 carrying pins 30 and 31 to which are secured a series of springs. The end plate 29 also carries the buckle 15 which is riveted or otherwise secured to the belt end. The end plate 28 is secured to the belt end in a like manner. To limit expanding action of the spring device 27 I employ a string or the like 32.

This spring device 27 cooperates with the springs 22 in the pad to hold the pad in proper position over the hernia and one is dependent upon the other to realize the benefits derived from the use of the truss. As an example the crotch strap 8 imparts a downward pull to the pad 14 under the yielding influence of the springs 22 and at the same time the spring device 27 develops a resilient or yielding pull to the pad in a direction transverse to the direction of the down-pull.

To protect the spring device 27 I enclose the same in a rubberized or other moisture proof cover which is secured around the belt end by means of snap fasteners 34. This cover 33 is made with a tab 35 which underlies the belt end under the buckle 15 as shown in Figure 2.

For the purpose of illustrating the salient features of the device I have selected a truss which is designed for treating a rupture on the right side. It will of course be understood the

same beneficial results will be realized by treating a rupture on the left side by rearranging the parts for the particular purpose. In the case of treating a double rupture the device will be made of a pair of pads each of which will be made alike and a pair of crotch straps will be used one for each pad.

From actual experience I have found that a truss made in accordance with my invention will serve in the capacity for which it is intended. It is comparatively cheap to produce, and the wearer does not experience the discomfort which is customary with abdominal trusses of this character.

Having thus described and shown an embodiment of this invention, what I claim and desire to secure by Letters Patent of the United States is:

In an abdominal truss, a pad, a shell like insert for said pad, said pad having a hollow interior fashioned for the reception of said insert, said insert having an inwardly offset oblong channel with attaching ears for said insert on opposite sides of said channel, a cover plate adapted to enclose said insert within the hollow of the pad, said cover plate having openings in the thickness thereof which register with like openings in the attaching ears of the insert to admit screws for anchoring the cover plate and said insert to the pad, a flanged slide carried on the cover plate on the back side thereof and slidably fitting the channel of the insert, a spring anchored at one end to the insert within the channel thereof with its opposite end anchored to the flanged slide and enclosed therein, said cover plate having a slot in the thickness thereof, and a crotch strap attaching member secured to said slide by means admitted through the slot in the cover plate and adapted for sliding movement on the face of the cover plate under the influence of the spring attached to the slide.

CHARLES NYGARD.
